PEG BOARD BRACKET

Marcus M. Tierney, 1911 Iglehart Ave., St. Paul, Minn.

Filed Dec. 20, 1956, Ser. No. 629,548

2 Claims. (Cl. 248—216)

This invention relates to a device comprising a bracket to be used for supporting objects for display or storage purposes and particularly in connection with a stationary wall or a movable display board formed of what is commonly known as a peg board. The type of bracket commonly used has an offset upstanding portion with the offset portion being loosely disposed within the opening in the peg board and depends a good deal to be held in position by the weight of the object supported. When not supporting an object, the bracket is quite loose and any tipping of the board or jarring action is sufficient generally to dislodge the bracket so that it is prone to fall out of position and drop from the board. It is desirable to have a bracket adapted to be easily positioned and to remain securely in position to be available for use at all times.

It is an object therefore of this invention to provide a bracket to be used in connection with a peg board and which is easily and quickly positioned for frictional engagement with said peg board.

It is another object of this invention to provide a bracket for a peg board with said bracket being adapted to be easily positioned and held in position by frictional engagement with said peg board and whereby the weight of an object supported by said bracket intensifies said frictional engagement.

It is a further object of this invention to provide a device forming a bracket and having a portion of a dimension to fit snugly in an opening in a peg board and having an object supporting means made integral therewith whereby the weight of said object places an upward stress on said portion causing it to increase its frictional engagement with said peg board within said opening.

It is also an object of this invention to provide a device comprising a trough-shaped member having a semi-cylindrical portion at one end and having a substantially flat terminal portion for easy insertion into and through an opening in a peg board, said semi-cylindrical portion having a dimension to fit snugly in said opening for frictional engagement therein and a shoulder formed on said member, and means integral with said member for supporting an object whereby the weight of said object places an upward stress on said semi-cylindrical portion causing it to bear against and bite into said peg board at the upper portion of said opening to strengthen said frictional engagement.

These and other objects and advantages of the invention will be fully set forth in the following description made in connection with the accompanying drawings in which like reference characters refer to similar parts throughout the several views and in which:

Fig. 1 is a view in side elevation of applicant's device in operating position with a supported object and a supporting wall surface shown in vertical section;

Fig. 2 is a view showing applicant's device in front elevation with a phantom view of a supported object and a supporting wall shown in dotted line;

Fig. 3 is a view showing applicant's device on an enlarged scale taken on line 3—3 of Fig. 2 as indicated by the arrows;

2

Fig. 4 is a view showing applicant's device on an enlarged scale taken on line 4—4 of Fig. 2 as indicated by the arrows;

Fig. 5 is a view similar to Fig. 3 showing a modification of applicant's device;

Fig. 6 is a view similar to Fig. 3 showing another modification of applicant's device; and

Fig. 7 is a view similar to Fig. 3, showing a further modification of applicant's device.

With reference to Figs. 1—4 of the drawings, a bracket 10 is shown adapted for use in connection with a peg board and for supporting objects thereon. Said device may be made of various types of material. It has been found to be convenient to stamp applicant's device out of sheet material, such as sheet metal or sheet aluminum of a suitable gauge. Said bracket 10 comprises a trough-like member 11. It is desirable to have said member 11 reduced or tapered in depth from substantially a mid-point towards its end for easy and convenient insertion into an opening. Said member 11 may be variously formed, but in the embodiment of applicant's device here illustrated, said portion is formed having an open top with a portion 11a at its front end substantially semi-cylindrical, a somewhat similar intermediate portion 11b of a reduced depth and a substantially flat terminal portion 11c. Said portions 11a and 11b are shown having substantially uniformly spaced sides. The top of said member 11 is shown to be in a single plane. Portions 11c and 11b are thus seen to respectively form step-like or offset portions in connection with portion 11a at the bottom of member 11. Thus it is seen that said portion 11 may be quickly and easily inserted in an opening 12 of a peg board 15.

As here illustrated, said portion 11a is of a length substantially equal to the length of said portions 11b and 11c and will be formed of a dimension to fit snugly into and engage the wall at the lower portion of said opening 12.

Integral with said member 11 is a plate member 16 having an offset portion 16a here shown to be approximately one-third of the distance downwardly from its top. Said plate member 16 is made integral with said portion 11 at the point of said offset portion 16a. Portion 16b extends upwardly from said offset portion and at each upper corner thereof is an outwardly inclined ear 16c. Extending below said offset portion 16a is a bottom portion 16d. As indicated in Figs. 2 and 4, said plate member 16 has integral therewith a pair of spaced members 11 identical in structure. Said member 16 may be provided with only one or a greater number of said members 11 as may be desired. Referring to Fig. 2, said members 11 are indicated as having been stamped out of said member 16.

The species of applicant's device as illustrated in Figs. 1—4 is especially adapted for use in supporting cartons, such as carton 17. Said carton will have a horizontal slit opening 17a at its rear side. The upper portion of plate member 16 will be disposed through said slit and into said carton. The wall of said carton above said slit will be supported on said offset portion 16a. Said ears 16c are turned outwardly for easy and convenient insertion of said upper portion of said plate member through said slit. The weight of said carton and the contents thereof will tend to cause the lower portion of plate 16 to bear against said peg board 15. Thus an upward stress will be placed on the rear portion of portion 11a and the sides thereof will bite into said peg board in the upper portion of opening 12 at the rear thereof. Thus there is provided substantial frictional engagement which is intensified and increased by the weight of the object supported.

When the object is removed, said portion 11a is of a dimension to fit snugly in the lower portion of said open-

ing and be frictionally held so there will be no tendency for it to be jarred loose or otherwise fall out. Said device is easily removed by tilting the upper portion of said plate member 16 slightly rearwardly and pulling forward.

A modification 20 of applicant's device 10 is shown in Fig. 5 in which member 21 and the portions indicated thereon are identical with member 11 and its corresponding portions as shown in Figs. 1-4. Integral with said portion 21 is a holding member 22 formed as a U-shaped hook member. Said member 20 may be made out of suitable rod-like material of a desired dimension and said portion 21 may be stamped out of the same material. Thus portions 21 and 22 may be easily and conveniently made out of a single piece of material.

In operation, said member 20 will function in a manner similar to said member 10 but instead of being specifically adapted for holding cartons, it is more generally adapted for holding any type of an object which may be suspended from a hook. Said member 22 in Fig. 5 illustrated as in its position when supporting a weighted object.

With reference to Fig. 7, a modification 25 is shown of applicant's device, as illustrated in Figs. 1-4. Applicant's device 25 comprises a trough-shaped member 26 similar in structure to said member 11 and having a semi-cylindrical portion 26a of a width to fit snugly in an opening in a peg board, an intermediate similar portion of reduced depth 26b, and a substantially flat terminal portion 26c. Said portions 26c and 26b are shown to respectively form steps or offset portions in connection with portion 26a at the bottom of said member 26. Said portions 26c and 26b will have their upper surfaces in a common plane. Said portion 26a will have its upper sides 26a' recessed slightly longitudinally to form a shoulder adjacent portion 26b. Integral with said member 26 is a plate member 27 which is identical in structure with said plate member 16.

Applicant's device 25 will be identical in operation to the device shown in Figs. 1-4. The weight of an object supported by plate member 27 will place an upward stress on portion 26a whereas its upper sides 26a' will bear against the peg board at the upper portion of the opening in which it is disposed. The rear portion of said sides 26a' forms a shoulder which will grip the upper rear portion of the opening and positively hold said bracket 25 in strong frictional engagement with the peg board.

With reference to Fig. 6, another modification 28 of applicant's device is shown in which member 30 is similar to said member 11 and is shown having a semi-cylindrical portion 30a, an intermediate portion of reduced depth 30b and a substantial flat terminal portion 30c. Said portions 30a, 30b, and 30c respectively form steps or offset portions at the bottom of member 30. Said member 30 will have its upper surface in a single plane with the exception that a shoulder 30d is formed intermediate portions 30a and 30b. Said shoulder may be of various heights but it is found that a slight height is satisfactory. Integral with said portion 30 is a plate member 32 identical in structure to said plate members 16 and 27.

In operation, applicant's member 28 is identical with applicant's members 10 and 25. When placed in operating position in an opening, portion 30a will snugly fit the lower portion of the opening for frictional engagement. The weight of an object supported on said plate member 32 provides an upward thrust at the rear of said portion 30a by tilting said member 28 forwardly and upwardly. The upper portions of the sides of said portion 30a will bear against the peg board in the upper portion of the opening in which member 28 is disposed. Said shoulder 30d will engage the upper portion of the surface at the rear of said opening and strengthen said frictional engagement. The intensity and strength of said frictional engagement will increase with the weight of the object being supported. Said member 20 is easily removed by pulling it forwardly in a horizontal plane and tipping

it slightly downwardly as it is being withdrawn through the opening.

Thus it is seen that I have provided a simply and easily made bracket to be used in connection with a peg board. Said bracket is easily placed in operating position and is held by frictional engagement in an opening in said peg board so that it is snugly held in position and not easily dislodged and whereby the frictional engagement is intensified and strengthened by the weight of an object supported by said bracket.

It will of course be understood that various changes may be made in the form, details, arrangement and proportions of the parts, without departing from the scope of applicant's invention, which, generally stated, consists in a device capable of carrying out the objects above set forth, in the parts and combinations of parts disclosed and defined in the appended claims.

What is claimed is:

1. A bracket for supporting a container having a horizontally disposed slit therein for use in connection with a peg board comprising an open top trough-shaped member having uniform width substantially throughout the length thereof and adapted to be disposed through an opening in said peg board, said width being such as to frictionally engage the sides of said opening, said member having a semi-cylindrical portion of a dimension to frictionally engage the adjacent side portions of said opening, an intermediate portion of reduced depth having an offset bottom portion in relation to said semi-cylindrical portion and a substantially flat terminal portion, said member having a concave curvature along the upper edge portions of said semi-cylindrical portion with said concave portion extending through said opening to form a shoulder adjacent said intermediate portion whereby when said bracket supports a weight it will be tipped forwardly and downwardly with said shoulders biting into the adjacent portions of said opening at the rear outer side thereof for positively holding said bracket secured in position and a plate member integral with said member at right-angles thereto having an upper offset portion whereby said offset portion may be disposed through said slit for supporting said container.

2. A bracket for supporting a container having a horizontally disposed slit therein for use in connection with a peg board comprising an open top trough-shaped member having uniform width substantially throughout the length thereof and adapted to be disposed through an opening in said peg board, said member having parallel upper edge portions lying in a common plane, said member having a semi-cylindrical portion of a dimension to frictionally engage the adjacent side portions of said opening, an intermediate portion of reduced depth having an offset bottom portion in relation to said semi-cylindrical portion and a substantially flat terminal portion, an upper standing shoulder formed on each of said edge portions at a point thereon to be positioned at the inner side of said opening in said peg board when said member is in operating position whereby when said bracket is supporting a weight, said bracket will be tipped to have said shoulders raised and bite into the adjacent outer side portions of said opening to hold said bracket securely in position and a plate member integral with said member and disposed in a plane at right-angles to said member, said plate member having an upper offset portion whereby said offset portion may be disposed through said slit to support said container.
